Patented Nov. 10, 1914.

UNITED STATES PATENT OFFICE.

HENRY W. KNIGHT, OF COLLINS, MISSISSIPPI.

PLOW ATTACHMENT.

1,116,826.

Specification of Letters Patent.

Patented Nov. 10, 1914.

Application filed April 8, 1914. Serial No. 830,444.

To all whom it may concern:

Be it known that I, HENRY W. KNIGHT, citizen of the United States, residing at Collins, in the county of Covington and State 5 of Mississippi, have invented certain new and useful Improvements in Plow Attachments, of which the following is a specification.

This invention relates to attachments to 10 plows, and has for one of its objects to provide a simply constructed device whereby the plow is guided or steered in its movement through the ground.

Another object of the invention is to provide 15 a device which may be adapted without material structural change to plows of various forms and sizes.

Another object of the invention is to provide 20 a device of this character which may be adjusted to operate at any required depth and to adjust the inclination of the mold-board relative to the shoe or landside.

With these and other objects in view the 25 invention consists in certain novel features of construction as hereinafter shown and described and then specifically pointed out in the claims.

The improved device may be applied without 30 material structural change to plows of various forms and sizes, and it is not designed therefore to limit the invention in this respect, but for the purpose of illustration the improved device is shown applied to a conventional plow, and in the 35 drawings illustrative of the preferred embodiment of the invention—Figure 1 is a side elevation of a portion of a plow with the improvement applied. Fig. 2 is a rear elevation with the beam of the plow in 40 section on the line 2—2 of Fig. 1. Fig. 3 represents the parts of the improved device separated and in perspective.

Corresponding and like parts are referred to in the following description and indicated 45 in all the views of the drawings by the same reference characters.

The beam of the plow is represented conventionally at 10, the standard at 11, and the hoe or moldboard at 12. The handles 50 are represented at 13 and the standard brace at 16, these parts being of the usual construction.

A shoe, represented conventionally at 17, is united preferably by a pivot 18, to the 55 lower end of the standard 11 and extends rearwardly thereof as shown. The stand-

ard of plows of this character is generally constructed in two parts and clamped to the opposite sides of the beam 10 by transverse bolts 19 and with a spacing block 60 indicated at 20 between the lower ends of the beam members.

The improved device comprises coacting bars 21—22 bearing upon opposite sides of the standard members 11 and likewise 65 upon opposite sides of the shoe 17. The members 21—22 are provided with means whereby they are adjustably coupled to the standard, and for the purpose of illustration an improved means for such adjustment is 70 shown consisting in forming a plurality of apertures through the members 21—22 as represented at 23, and through which one of the clamp bolts 19 is pivoted. By this means the bolt performs the two fold function of a means for clamping the standard members to the beam and likewise as a means for securing the members 21—22 in 75 position at their upper ends. By providing a plurality of the apertures 23 the members 21—22 may be adjusted relative to the beam members within the range of the apertures.

Bearing upon the outer face of the member 21 is a plate 24, preferably formed with 80 a cutting edge at its lower terminal and likewise provided with a plurality of longitudinal apertures 25. The pivot bolt 26 by which the members 21—22 are coupled to the shoe 17 is likewise utilized to pass 85 through one of the apertures 25 and thus support the member 24 in position. An additional clamp bolt 27 may also be employed through the apertures 25 and likewise through the members 21—22 to more 90 securely support the member 24 in position. By this simple means the member 17 is supported adjustably in position, while the member 24 is likewise supported adjustably in position so that the depth to which it 95 operates below the lower line of the shoe may be controlled.

With a device thus constructed, it will be obvious that as the plow is drawn through the ground the member 17 cuts into the soil 100 below the line of the shoe and serves as a guard or steering member to control the movement of the plow and prevent lateral displacement.

Having thus described the invention, what 105 is claimed as new is:

1. In a plow including a beam and stand-

ard, a shoe member connected to the standard and extending rearwardly thereof, a brace member adjustably connected at one end to the standard and pivoted at the other end to the shoe, a steering member having a cutting terminal, and means for adjustably clamping said steering member to the brace and maintaining the steering member in constant longitudinal alinement with the brace.

10 2. In a plow including a beam and standard, a shoe member connected to the standard and extending rearwardly thereof, co-acting brace members bearing at opposite sides of the standard and of the shoe, means

for adjustably coupling said brace members to the standard, means for pivoting the brace members to the shoe, and a steering member having a cutting terminal, means for adjustably clamping said steering member to the brace and maintaining the steering member in constant longitudinal alinement with the brace. 20

In testimony whereof I affix my signature in presence of two witnesses.

HENRY W. KNIGHT.

Witnesses:

D. A. DAVIS,
G. C. Todd.
